UNITED STATES PATENT OFFICE.

EDMOND HECTOR COATES, OF CHATTANOOGA, TENNESSEE, ASSIGNOR TO J. BRUCE CARROLL, OF CHICAGO, ILLINOIS.

COUPON-BOOK.

982,127.

Specification of Letters Patent. Patented Jan. 17, 1911.

Application filed August 9, 1909. Serial No. 511,960.

To all whom it may concern:

Be it known that I, EDMOND HECTOR COATES, a citizen of the United States, residing at Chattanooga, in the county of 5 Hamilton and State of Tennessee, have invented certain new and useful Improvements in Coupon-Books; and I do hereby declare the following to be a full, clear, and exact description of the invention, such as 10 will enable others skilled in the art to which it appertains to make and use the same.

This invention relates to coupon or similar books, and has for an object to provide means whereby coupons of the desired 15 denomination become readily accessible.

A further object of the invention is to provide in book form coupons of a plurality of denominations, and of substantially the same size, but so mounted in a book that the 20 ends of coupons of different denominations are visible when the cover of the book is open.

Specifically the object of the invention is to provide in book form a plurality of 25 leaves each embodying a plurality of coupons and representing a plurality of denominations and so arranged that when the front cover of the book is open, leaves of 30 coupons of different denominations are visible.

With these and other objects in view, the invention comprises certain novel constructions, combinations and arrangements of parts, as will be hereinafter fully described 35 and claimed.

In the drawings:—Figure 1 is a view of 40 an embodiment of the present invention shown with the cover open exhibiting one leaf of coupon in full and the ends of other leaves of coupons of other denominations. Fig. 2 is a view in edge elevation of the 45 coupon book with the leaves separated at the outer ends showing the difference in lengths of such groups of leaves.

Like characters of reference designate corresponding parts throughout the several views.

In the ordinary binding of books of 50 coupons, tickets or the like, which are composed of leaves of the coupons or tickets perforated to be separated singly or as the case may be, and of different denominations, it is customary to produce the leaves of similar 55 lengths and when it is desired to remove a coupon of a required denomination, it is

necessary to turn the leaves to find such coupons. As coupons are ordinarily handled by busy people the waste of time thus employed, while inconsiderable in a single case, is objectionable and in the long run amounts 60 to an objectionable feature.

In the present instance, in Fig. 1 is illustrated a book containing coupons of three denominations, twenty-five cents, ten cents and five cents, and as shown at Fig. 2 two 65 leaves of the twenty-five cents, three leaves of the ten and six leaves of the five cent coupons are bound together. Of course, it is to be understood that any number of coupons of each denomination may be employed, 70 without departing from the spirit of the invention.

As shown in the drawing covers 10 and 11 are folded over and form a binding of a plurality of single leaves composed each of 75 a plurality of coupons as represented on the first leaf at 12. It is desirable that all of the coupons be similar or substantially similar in size so that they may be properly filed, punched, tied or otherwise stored. For this 80 purpose the coupons upon the various leaves are made of the same size but in binding more margin is left at the top for the coupons which appear nearer the back of the book. As shown the front leaves shown at 85 12 are shorter than the leaves 13 which in turn are shorter than the leaves 14 although the coupon making up the several leaves 12, 13 and 14 are of the same size, the difference 90 being in the amount of margin left at the top or bottom ends of the leaves.

As will be apparent from an inspection of the figures the opening of the front cover 10 at once reveals in full one leaf of coupons of one denomination and the extended ends of 95 coupons of other denominations. If it is desired to remove from the book coupons of denominations other than those appearing upon the first leaf, the user has but to place his thumb or finger upon the extended end of the leaf designated by the coupon desired and by turning the leaves in front, leaves of coupons of the required denomination are at once made accessible. I wish it to be understood that each of the series of coupons of 100 the book having the different denominations thereon is provided with a number "1244 F" as shown in Fig. 1 of the drawings; this number designates the number of the book 105 from which the coupons are torn so that 110

reference to the same may be had if for any reason should occasion require that it be done. By this means much time in turning leaves to arrive at leaves of coupons of the right denomination is avoided.

While coupons of three denominations as indicated have been shown in the drawings it is to be understood that such number is only indicative of the use of the invention and that any number more or less than shown would fall equally within the scope of the invention.

What I claim is:—

A coupon book comprising a plurality of groups of leaves provided with binding margins at one end and detachably connected therewith, and divided by weakened lines into a plurality of coupons of the same size arranged in groups, the binding margins of the several groups increasing in width from the front to the back of the book and each

group having its leaves provided with the same indicia marked thereon but that of the groups being of different denomination and each of the groups having their ends extending one below and beyond the other so as to provide marginal extensions having marked thereon indicia corresponding to the indicia marked on the different groups of leaves of said book, and the book and each of the coupons of the different groups having the same number designating the number of the book from which they were detached, and each group of a distinctive color different from that of the other groups.

In testimony whereof I affix my signature in presence of two witnesses.

EDMOND HECTOR COATES.
